UNITED STATES PATENT OFFICE

2,441,020

BOATBUILDER'S CLAMP

Laurits A. Hansen, Philadelphia, Pa., and Karl E. Forsberg, Pitman, N. J.

Application March 28, 1945, Serial No. 585,292

1 Claim. (Cl. 144—298)

1

Our invention relates to new and useful boat-builders' clamps, especially such clamps as are employed in the construction of wooden boats, and has for one of its objects to provide clamps that can be easily and quickly applied to or removed from the ribs of a boat in the course of construction and thereafter operated to force the side planks into proper position for securing to said ribs.

Another object of the invention is to provide a clamp that is, practically, automatically clamped to a boat rib as the same is operated to force a side plank into place.

Another object of the invention is to construct a clamp of the kind mentioned comprised of a body having a stationary offset jaw at one end, an offset movable jaw slidably mounted on the body, and a pressure screw at the opposite end of said body to engage the edge of a side plank of a boat on which the clamp is temporarily mounted.

A further object of the invention is to form the body substantially of sickle shape to have the jaws practically opposite each other when the clamp is in use.

Other objects of the invention are, to provide supplemental jaws; to provide either or both of said supplemental jaws with roughened rib engaging surfaces; and to provide serrations on the inner periphery of the body to insure the retention of the movable jaw in its adjusted position.

With the above and other objects in view this invention consists of the details of construction and combination of elements hereinafter set forth and then designated by the claim.

In order that those skilled in the art to which this invention appertains may understand how to make and use the same we will describe a structure in detail referring by numerals to the accompanying drawing, forming a part hereof, in which:

Fig. 1 is a view of the clamp looking at the concave edge thereof.

Fig. 2 is a perspective view of the clamp.

Fig. 3 is a side elevation of the clamp showing it on a boat rib and holding a side plank in place.

Fig. 4 is a side elevation of the clamp viewed from the opposite side to that illustrated in Fig. 3.

Fig. 5 is a section on the line 5—5 of Fig. 3.

In carrying out our invention as herein embodied 10 represents the body of generally sickle shape although this configuration can be varied. At one end of the body is a stationary jaw 11, preferably in the form of a post, projecting from

a side face at one end of said body and therefore is offset.

A movable jaw 12, also preferably in the form of a post, projects from a side face of a yoke 13 which is slidably mounted on the body 10 intermediate the ends thereof, so that said movable jaw is offset, similar to the stationary jaw 11 and on the same side of the clamp body as said jaw 11.

While not absolutely necessary, the inner periphery or concave edge of the body, preferably, is roughened or serrated at 14 with which the back edge of the yoke or a single tooth 15 thereon coacts to positively prevent the movable jaw, through its yoke, from being accidentally released as pressure is applied.

Under some conditions it is desirable to have extended flat contact surfaces on the jaws and for this purpose I provide supplemental jaws 16 rotatably mounted on the stationary and movable jaws. Each supplemental jaw comprises a flat plate 17 having a very slightly roughened or knurled contact surface, and a sleeve 18 having a snug fit on the respective stationary and movable jaws but capable of rotation. These supplemental jaws can be placed in position or removed at will by merely slipping them on or off of the permanent stationary and movable jaws.

On the opposite or outer end of the body 10 is mounted a screw supporting post 19 for rotation and this post 19 also projects from the same side of the body as the stationary jaw. A neck portion of the post 19 projects through the body and has a head 20 formed on the far end.

A screw spindle 21 is threaded through the screw supporting post and on one end of said spindle is a handle 22 and on the other end is swiveled a foot 23 so as to assume different angular positions relative to the axis of the spindle and to remain stationary while said spindle turns.

In practice, the clamp is applied to a rib 24 of a boat in the course of construction, by slipping the clamp laterally over the rib so that the jaws engage opposite edges of said rib and the body 10 lies along one side of the same rib. The movable jaw is then adjusted towards the rib until said jaw is definitely in contact with said rib. The screw spindle 21 now is swung to a position which will cause the foot 23 to engage an edge of a side plank 25, which may be fastened at one end while the major portion, probably, will not be in the final desired location. As the screw spindle is screwed forwardly the necessary pressure will be applied to the plank to force it against the rib and also towards and into the

desired location. As usual, the plank has been previously steamed and since the direction of the applied pressure is in an oblique line said plank will be moved in a generally diagonal path to hold it against the rib and force it edgewise into position where it will be held until fastened in place. During this operation the screw supporting post 19 can rotate and the foot can oscillate to accommodate itself to the various relative positions between the screw spindle and the plank.

At the same time a counter pressure is applied to the outer overhanging end of the clamp body thus having a tendency to cant the clamp so that the jaws will more firmly grip the rib.

After the plank has been fastened, the screw spindle is backed off sufficiently to relieve the pressure and the clamp then may be removed without the necessity of releasing the jaws. This overcomes the usual requirement of knocking out wedges and withdrawing fastening devices from blocks attached to the rib.

While we have shown the clamp in a position on the rib for exerting a generally upward pressure, said clamp can be inverted and applied to the opposite side of said rib and a plank can be forced into position from another direction.

Of course we do not wish to be limited to the exact details of construction herein shown and described as these may be varied within the scope of the appended claim without departing from the spirit of our invention.

Having described our invention what we claim as new and useful is:

A boatbuilder's clamp comprising a generally sickle shaped body, a stationary post projecting from one side at one end of said body, a screw supporting post journaled in the other end of said body and projecting from the same side thereof as the stationary post, a screw spindle threaded through said supporting post, a yoke slidably mounted on the body intermediate its ends, another post projecting from a side face of the yoke in the same direction as the stationary post, and jaws removably and rotatably mounted on said posts, each jaw including a flat plate and a post-engaging sleeve as an integral structure.
